UNITED STATES PATENT OFFICE.

CHARLES C. RUPRECHT, OF MIDWAY, FLORIDA.

ELECTROLYTIC RECTIFIER.

1,223,114.

Specification of Letters Patent. Patented Apr. 17, 1917.

Application filed April 22, 1918. Serial No. 92,963.

To all whom it may concern:

Be it known that I, CHARLES C. RUPRECHT, a citizen of the United States, and a resident of Midway, in the county of Gadsden and 5 State of Florida, have invented a new and Improved Electrolytic Rectifier, of which the following is a full, clear, and exact description.

This invention relates to electrolytic rectifiers, and has for its general objects to improve the construction so as to render the rectifier more reliable and free from the objections in the ordinary type of rectifier.

The ordinary electrolytic rectifier has certain well-known objections and is difficult to keep in the most efficient state by persons of ordinary skill.

In the operation of the rectifier the solution is decomposed by the passage of electric 10 current, hydrogen and oxygen being liberated, and the salt or salts or chemical being decomposed and changed. By continued use the solution loses more and more of the original salts which may assume a non-soluble 15 form, and the resulting combination deposits at the bottom of the retainer. The results of this action are the ever-increasing electrical resistance of the solution and the failing action of the remaining solution in 20 the forming of the insulating film necessary to the action of the rectifier. The efficiency 25 of the rectification is also affected by the increased temperatures of the solution due to its increased resistance, and a point is soon 30 reached where the rectification fails and the electrodes of the rectifier are seriously corroded by the weakened solution. To guard 35 against this trouble manufacturers have used very large retainers for the solution, 40 and have given urgent and detailed instructions as to when and how to renew the solutions. It is difficult, however, to impress the user with the necessity of carefully attending to these details, and in fact it is hard 45 for the layman to determine just the right time for stopping the use of the device until it has been recharged.

To overcome these objections I contemplate the use of means whereby the salts or 50 chemicals in excess of the saturation point will be disposed in the circulatory current in the electrolyte, whereby the solution will be kept saturated at all times and maintain its maximum conductivity, both of heat and 55 electricity; the rectification is also main-

tained practically at a constant efficiency, and a constant combination of the salts with the solvent tends to cool the solution, which helps to maintain the rectifier in its best working condition. The placing of the salts 60 in the circulatory path of the solution and away from the active electrodes causes recrystallization of the salt on the mother crystals in the receptacle or retainer and not at the electrode or any other place where 65 they would detrimentally affect the working. Such over saturation might occur in case the working solution of the rectifier was increased in temperature by excessive loads, and on cooling or during periods 70 when not in operation, some crystallization may occur.

For a more complete understanding of the invention reference is to be had to the following description and claims taken in connection with the accompanying drawing which illustrates certain embodiments of the invention and wherein

Figure 1 is a vertical section of a rectifier; Fig. 2 is a plan view thereof; 80

Fig. 3 is a sectional view of a modified form of rectifier; and

Fig. 4 is a sectional view of a further modification.

Referring to the drawing, 1 designates the 85 jar or body of the rectifier, which, as shown, in Figs. 1, 2 and 4, may be formed with a small secondary chamber 2 connected at its upper and lower ends by ports 3 and 4 with the chamber 5 of the body 1, the two chambers 90 being so communicating that the electrolyte 6 can freely circulate upwardly in the chamber 2, out of the top thereof, downwardly in the chamber 5, and therefrom into the bottom of the chamber 2. In this manner the electrolyte is kept in circulation along the electrodes 7 and 8. Arranged slantly in the body 1 is a perforated plate 9 extending from the top of the body at one side to the bottom at the opposite 95 side, this plate coöoperating with the wall of the body at a point opposite from the chamber 2 to form a retainer or holder for the salts or chemicals 10. Between the plate 9 and the wall of the body 1 at a point directly under the port 3 is a perforated baffle 11 which serves to cause a circulation of the electrolyte downwardly through the chemicals 10. It will be noted that the chemicals are positioned at the remotest 100

105

110

point from the electrodes which, together with the fact that the solution circulates through the chemicals, maintains the solution in its proper saturated condition, and 5 consequently the life of the rectifier is greatly increased, and recharging is necessary only at long intervals.

Another means for holding the chemicals is shown in Fig. 3, wherein 13 is a cylindrical 10 or other retainer which has apertured walls so that the electrolyte can freely circulate through the body of chemicals which is kept as far as possible from the electrode 14.

In the construction shown in Fig. 4 the 15 body 1^a is formed with a sediment collecting well 15 at its bottom, from which the sediment can be drawn off through a valve 16. By opening the valve the sediment can 20 be drawn off without drawing off the solution during the operation and use of the device.

From the foregoing description taken in connection with the accompanying drawing, the 25 advantages of the construction and method of operation will be readily understood by those skilled in the art to which the invention appertains, and while I have described the principle of operation, together with the device which I now consider 30 to be the best embodiment thereof, I desire to have it understood that the device shown is merely illustrative and that such

changes may be made when desired as fall within the scope of the appended claims.

Having thus described my invention, I 35 claim as new and desire to secure by Letters Patent:

1. An electrolytic rectifier comprising a container for the electrolyte, a holder disposed in the container for holding chemicals 40 submerged in the electrolyte, said holder having perforations in the portions above and below the chemicals for permitting the electrolyte to circulate downwardly through the chemicals from the top and laterally 45 out of the chemicals at the bottom, and electrodes in the electrolyte at the side of the holder opposite from that holding the chemicals.

2. An electric rectifier or condenser comprising a receptacle, an electrolyte therein, there being a sediment collecting well in the bottom of the receptacle, means for drawing off the sediment from the bottom of the well, means in the receptacle for holding 50 chemicals above the well and in the path of circulation of the electrolyte, and electrodes in the electrolyte at a point spaced from the chemicals.

CHARLES C. RUPRECHT.
